(57) **CLAIM**

The ornamental design for a cockpit light bezel, as shown and described.

DESCRIPTION

FIG. 1 is a front perspective view of a cockpit light bezel showing our new design;

FIG. 2 is a back perspective view thereof;

FIG. 3 is a bottom view thereof;

FIG. 4 is a top view thereof;

FIG. 5 is a front view thereof;

FIG. 6 is a back view thereof;

FIG. 7 is a first side view thereof; and,

FIG. 8 is second side view thereof.

The broken lines illustrate structure and environment that form no part of the claimed design.
